UNITED STATES PATENT OFFICE.

JOSEPHUS C. CHAMBERS, OF CINCINNATI, OHIO, ASSIGNOR OF THREE-FOURTHS TO CHARLES O. LOCKARD, GEORGE T. STEDMAN, AND GOODRICH H. BARBOUR, ALL OF SAME PLACE.

SELF CLOSING AND LOCKING HATCHWAY-DOOR.

SPECIFICATION forming part of Letters Patent No. 248,404, dated October 18, 1881.

Application filed August 5, 1881. (No model.)

To all whom it may concern:

Be it known that I, JOSEPHUS C. CHAMBERS, of Cincinnati, in the county of Hamilton and State of Ohio, have invented new and useful 5 Improvements in Self Closing and Locking Doors of Elevator-Hatchways, of which the following is a specification.

In order that my invention may be fully understood, I will proceed to describe it with reference to the accompanying drawings, in which—

Figure 1 is a top view of the hatchway and surrounding parts, the doors being shown closed and locked, and the top of the elevator-frame. Fig. 2 is a bottom view thereof, the elevator having passed above. Fig. 3 is a top view, the floor-boards being removed, the doors opened by the elevator, showing the locking-plates in retracted position, and the elevator-platform *in situ*, and a horizontal section of the elevator-frame on the line of the platform. Fig. 4 is a vertical section on a larger scale on the line 4, Fig. 1, looking in the direction of the arrow. Fig. 5 is a vertical section on a larger scale on the line 5, Fig. 1, looking in the direction of the arrow. Fig. 6 is a vertical section on the line 6 6, Fig. 3, showing the flanges which work between the rollers to open and close the hatchway-doors, one of which is 25 adapted to push on the locking-plate to unlock it.

1 may represent a portion of a warehouse-floor surrounding a hatchway.

2 may represent the customary stanchions. 33^a are a pair of sliding doors, of which each door has two pairs of rollers, 4 4^a, that engage the roller 4 in front and roller 4^a in rear of flanges 5, that project laterally from cam-braces 6 of elevator 7. The said doors are capable of 40 sliding toward or from one another in suitable guides, 8, either above or below the wareroom-floor or in suitable recesses, 9, thereof. Of the said doors one door, 3, has a pair of studs, 10 10. The other door, 3^a, has a sliding bar or

plate, 11, from which project hooks or catches 45 12 12, which, in the normal position of the bar, interlock with said studs, as shown in Fig. 1. This automatic interlocking is accomplished by means of spring 13, which acts to press the plate outward. As the elevator ascends or descends a corner of one of its advancing flanges, 5, impinges against a tappet, 14, upon bar 11, and pushes the bar in direction of arrow, (see Fig. 5,) so as to cause disengagement of hooks 12 12 from studs 10 10. At the same instant 55 the vertical portions 15 of the braces 6 enter and pass between each pair of rollers 4 4^a, which, acted upon by the oblique portions 16 of said braces, these portions operate to retract the now unlocked doors to the entirely 60 open position, this position being maintained by the vertical portions 17 of said braces 6. Finally, as the corresponding oblique portion 18 at the remote end of the elevator reaches the rollers, a precisely reverse action commences and continues until the vertical portions 65 of the braces at that end reaching the rollers the doors become completely closed, and on the brace escaping from contact with the rollers the spring resumes its functions and restores the hooks 12 12 to lock. On engagement of the hooks 12 12 upon the studs 10 10 70 the doors are locked not only against lateral, but also against vertical, displacement.

The locking mechanism may be either above 75 the doors, as shown, or beneath them.

I claim as new and of my invention—

The combination, with a pair of sliding doors or shutters, 3 3^a, of the elevator-brace 6 5 15 16 17 18, tappet 14, sliding bar 11, spring 13, 80 hooks 12 12, and studs 10 10, for the purposes set forth.

In testimony of which invention I hereunto set my hand.

JOSEPHUS C. CHAMBERS.
